CLAIM

The ornamental design the a snap down lid for airtight canister, as shown and described.

DESCRIPTION

FIG. 1 is a perspective view of a snap down lid for airtight canister showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the snap down lid for airtight canister shown in an opened state;

FIG. 10 is an exploded perspective view of the snap down lid for airtight canister;

FIG. 11 is a perspective view of the snap down lid for airtight canister where the snap down lid for airtight canister is in a first configuration of use;

FIG. 12 is a perspective view of the snap down lid for airtight canister where the snap down lid for airtight canister is in a second configuration of use;

FIG. 13 is a perspective view of the snap down lid for airtight canister where the snap down lid for airtight canister is in a third configuration of use;

FIG. 14 is a perspective view of the snap down lid for airtight canister where the snap down lid for airtight canister is in a fourth configuration of use; and,

FIG. 15 is a perspective view of the snap down lid for airtight canister where the snap down lid for airtight canister is in a fifth configuration of use.

The broken lines shown in FIGS. 1–10 depict portions of the snap down lid for airtight canister that form no part of the claimed design. The other broken lines in FIGS. 11–15 showing airtight canisters depict environment and form no part of the claimed design.

1 Claim, 15 Drawing Sheets
